UNITED STATES PATENT OFFICE.

GEORGE CLEMENTS, OF CHICAGO, ILLINOIS, ASSIGNOR TO CLEMENTS MFG. CO., OF CHICAGO, ILLINOIS, A CORPORATION OF ILLINOIS.

VACUUM CLEANER.

Application filed August 4, 1921. Serial No. 489,672.

To all whom it may concern:

Be it known that I, GEORGE CLEMENTS, a citizen of the United States, residing at Chicago, in the county of Cook and State 5 of Illinois, have invented a certain new and useful Improvement in Vacuum Cleaners, of which the following is a specification.

My invention relates to a vacuum cleaner, and particularly to a vacuum cleaner in 10 which a brush, lying in the suction inlet, is frictionally driven from floor contacting rollers. One object of my invention is to provide a brush bearing, which shall at the same time support the brush and hold 15 the brush yieldingly in contact with the frictional brush-driving rollers. Another object is the provision of a guard for the suction inlet which shall prevent the penetrations of the carpet edge into the suction 20 inlet. Other objects will appear from time to time in the course of the specifications. I illustrate my invention more or less dia- 25 grammatically in the following drawings, wherein,

Fig. 1 is a view from below of the suction inlet, showing the brush bearing and driving means and the brush guard.

Fig. 2 is a section on the line 2—2 of Fig. 1.

Fig. 3 is a section on the line 3—3 of Fig. 1.

Fig. 4 is a section on the line 4—4 of Fig. 1.

Like parts are represented by like letters 35 and numbers throughout the drawings.

A is a suction inlet casing being formed with substantially parallel inlet lips A' A' connected to the usual type of vacuum cleaner, not herein shown.

40 Rotating within the suction inlet is a brush shaft B, and mounted thereon, a brush cylinder or body B' which supports the brush bristles B². At the extremities of the shaft B are mounted the rollers B³ 45 B³ through which the shaft and brush are rotated, from the floor contacting wheels B⁴ B⁴ which are pivoted in the rearward projections B⁵ from the inlet lips A'. The roller B³ is preferably provided with an 50 anti-frictional coating or surface B⁶ which may be in the form of a rubber band or rim about the roller.

Mounted at C—C in the forward side of the casing A are S shaped springs C' C' 55 which are preferably formed of the large

bend C² and the small bend or loop C³. The springs are so formed that the loops C³ engage and support the ends of the shaft B and not only support the brush at the proper distance from the floor, but tend to 60 press the rollers B³ against the floor engaging rollers B⁴. The spring C' is light and is therefore provided with a relatively stiffer reinforcing spring C⁴ which tends to prevent deformation and depression of the 65 lighter spring. Both springs are held against sideways movement by the lug A².

Along the inside surface of each suction inlet wall A' is a groove D substantially parallel with the ground. Mounted in these 70 grooves is a zig-zag guard D' preferably of wire, which is so bent that alternate turns or corners of the wire engage opposed sides of the inlet nozzle and seat wire or guard in the opposed grooves. 75

While I have illustrated a working device which is actually being manufactured and sold, it is obvious that many variations in size, number, shape, and relation of parts might be made without departing from the 80 spirit of my invention. The nature of the spring bearing and the method and location of attachment might be changed. I therefore wish my description and drawings to be taken broadly and as merely illustrative 85 of the nature of my invention.

The use and operation of my invention are as follows: I have illustrated a type of vacuum cleaner in which a light brush is rotated in the suction inlet, being driven 90 from ground contacting rollers, which in turn contact rollers on the brush shaft. In order to prevent wear of the rollers on the brush shaft from affecting the drive of the brush, and in order to prevent slipping of 95 the brush in relation to the traveling floor contacting rollers, I provide a leaf spring bearing, roughly S-shaped, one end of which forms a partly closed loop, which supports the end of the brush shaft. The outer 100 end of the spring is secured to the front of the suction inlet casing. The spring is so shaped that this lower loop supports the brush against gravity. The spring further tends to push the brush shaft to the rear, but 105 its excursion is limited by the engagement of the rollers on the brush shaft with the ground contacting rollers, the spring forcing them into close frictional contact therewith.

- The brush guard is illustrated as a simple zigzag wire, the opposite cleaners and ends of which fit in grooves inside of and parallel with the lips of the suction inlet. 5 This wire has sufficient spring tension to set itself firmly within the grooves, but can easily be removed by manual pressure. It will be noted that the point where the restricted passage enters the bag body proper 10 is an inch or more away from the connection of the restricted neck with the cleaner casing. This prevents the lodging of dust or foreign material about the bottom of the bag as when a tube or loose flap is used, such 15 material being likely under those circumstances to form a solid mass or ring about the bag inlet, with the resultant constriction of the exhaust passage and the reduction in the efficiency of the cleaner. This result will 20 be obtained in a variety of ways, but in the present application is obtained by having

the body of the bag stop short of the point where the restricted neck is connected to the casing, and by further forming the tapered inlet passage largely of the side of the bag 25 itself, so that there is no interval between the inlet passage or tube and the bag wall into which the dust can penetrate to form the above mentioned constricting mass.

I claim:

In a vacuum cleaner, a suction nozzle, the opposed lips of said nozzle being grooved in a plane adjacent to and parallel with the lower edge of the nozzle, and a guard element adapted to be yieldingly and remova- 30 bly mounted in the suction nozzle, portions 35 of said guard element penetrating said grooves on each side of the nozzle.

Signed at Chicago, county of Cook and State of Illinois, this 28th day of July, 1921

GEORGE CLEMENTS.
